(57) **CLAIM**

(22) Filed: **May 16, 2007**

We claim the ornamental design for an aircraft interior end cap, as shown and described.

(30) **Foreign Application Priority Data**

DESCRIPTION

Nov. 16, 2006 (EM) 000622220-0001
Nov. 16, 2006 (EM) 000622220-0002
Nov. 16, 2006 (EM) 000622220-0003
Nov. 16, 2006 (EM) 000622220-0004

FIG. 1 is a front perspective view of an aircraft interior end cap showing our new design;

(51) **LOC (9) Cl.** 12-07

FIG. 2 is a front elevation view thereof;

(52) **U.S. Cl.** D12/345

FIG. 3 is a left side elevation view thereof; and,

(58) **Field of Classification Search** D12/317-319,
D12/345, 400, 426; 244/117 R, 118.5, 119-121,
244/129.3; 52/64

FIG. 4 is a front perspective view of the aircraft interior end cap of FIG. 1 shown as it would be when in use.

See application file for complete search history.

The broken lines in FIG. 4 showing a portion of the interior of an aircraft illustrate environmental structure and form no part of the claim.
